UNITED STATES PATENT OFFICE.

THOMAS OWEN BATES, OF LIVERPOOL, ENGLAND.

MACHINERY FOR MAKING CUP-WAFERS, SUGAR-WAFER BISCUITS, AND THE LIKE.

No. 880,497.

Specification of Letters Patent.

Patented March 3, 1908.

Application filed November 20, 1906. Serial No. 344,228.

To all whom it may concern:

Be it known that I, THOMAS OWEN BATES, a subject of the King of England, residing at Liverpool, in the county of Lancaster, England, have invented new and useful Improvements in Machinery for Making Cup-Wafers, Sugar-Wafer Biscuits, and the Like, of which the following is a specification.

This invention has reference to machinery for making cup wafers of various shapes, sugar wafer biscuits, and the like; and it relates more particularly to that type in which a plurality of sets of cooking plates are mounted on a revolving part, and move in sequence round about an axis, being heated during their revolution, on both sides, so that the cooking and manipulation of the whole machine requires the attention of only one person, and the whole of the operations are performed in sequence in the one machine.

The invention has primarily for its object and effect, to provide a machine of inexpensive and simple construction of the type referred to, and one in which the cooking, and its manipulations, can be carried out with ease and regularity, and the articles produced are of good quality, and made rapidly, and with little wastage or breakages.

In the drawings hereto annexed, the machine constructed according to this invention, that is, involving the improvements is illustrated, and it will be described by the aid of these drawings; the novel characteristics of the machine being set out in the claiming clauses concluding the specification.

In the drawings, Figure 1 is an end elevation; Fig. 2 is a side elevation in section; and Fig. 3 is a plan.

The machine according to this invention has two outside frames, namely, a front frame 1, and a back frame 3; and within these frames there is a rotary frame 5 for carrying and revolving the plates in which the cups, biscuits, or other articles are made; this rotary frame 5 consisting mainly of two parallel plates connected together and mounted on hollow trunnions 7 and 8, fitting and working in bearings 2, 4, of any suitable kind in the front and back frame plates 1, 3.

Extending through the center of these trunnions 7 there is a hollow shaft or tube 8 for supplying heating or cooking gas to a burner 9, which is disposed within and under the lower or inner plates of the apparatus when they reach the top position.

The parts in which the batter is intro-

duced and cooked consist of a lower plate 11, in which the matrices 12 for holding the material are carried, and an upper plate or cover 13; these plates being of any known suitable form. And between these plates there may be a movable plate for stripping or starting the cups, biscuits, or the like, off the die cores when the upper plate or cover 13 is opened, after they have been cooked.

The rotating frames 5 are made of polygonal form, that shown in the drawing being hexagonal, with six sets of plates 11, 13, fitted to and employed in connection with them.

The lower or inner plates 11 are fixed on the edges of the frames 5, and the outer plates or covers 13 are hinged by a hinge 15, to these lower plates; and at the front, on the front frame 1 a projection (16, 19,) is provided which operates in connection with parts hereafter described, by means of which, when the rotary carrier frames 5 are revolved, say $\frac{1}{2}$ of a revolution, and one of the cover or upper plates 13 is coming towards the top position, it is unlocked, and that plate or cover which is just passing down from the top position is locked, and remains held and locked till it arrives at the opposite side.

The projecting part referred to is in two portions or sections, 16, 19, one 19, at the upper part, which effects the unlocking action, having an upwardly extending flange 17, which is inclined on its inner surface—see Fig. 2—so as to engage with the inner end of the catch, 20, which locks the two plates 11, 13, together, and pull it away from them, as hereafter described; while the other portion 16 extends practically all round in an even vertical plane, except at the leading and leaving edges, which are inclined or tapered inwards, and which, by one of these inclined parts, forces the said catch into engagement with the lower plate, moving it in the opposite direction to that just described, and holding it in this position until it comes round again to the unlocking position, which is near the top where this part 16 ceases, and the part 19 is placed. This unlocking action takes place as the plates come up to the top position, and the locking action takes place as they move away from this position, after the plates or matrices are re-charged with fresh batter.

There are gaps at 18 between the unlocking and locking portions 16, 19, of these projecting parts, to allow of the swinging to and fro of the plate catches 20 referred to. With

regard to the catches 20, each is hinged to the end of the upper plate 13, a catch of course being used in connection with each couple of plates.

5 The catch is weighted by weights 21, which normally tends to press it out of engagement with the lower plate 11, and holds it in the desired position when the plate 13 is brought down to engage with the plate 11; 10 that is, it prevents this catch from fouling the plate 11 when so brought down. It is the lower end of this catch 20, with which the flange 17 of the upper projecting part 19, and also the other part 16 operates, as 15 above described.

With regard to the opening and closing action of the plates 13, when one of these comes to the upper position, and the matrices 12 are to be emptied of the cooked 20 articles, and recharged with fresh batter, the upper plate or cover 13 carrying the dies or cores is unlocked, and it is raised, being assisted by counter balance weights 22, and is held there by the weights during these 25 operations. These weights 22 in one arrangement—that as shown in the drawings—are mounted on spindles 23 supported in bearings 24, fixed on the back stationary frame plate 3, and coincident with the axis 30 of the hinge 15 of the upper plate or door 13; and they are adapted to be connected up with and act on the then upper plate 13 by upper levers 25, fixed at their back ends to the spindles 23, and carrying at their front 35 end—which are connected together by a bar 26 on an engaging part 27, with which the projecting part 14 on the end of each upper plate 13 is adapted to engage or move, as a pair of plates come to the top position.

40 In action, as a pair of plates are brought by the revolving gear round towards the upper and horizontal position, the engaging part 27 will be held down, by one of the curved projecting parts 6 on the face of the 45 front revolving frame 5, which will then lie over the inwardly projecting part 28 of the device 26. Then, when the complete upper position is reached by the plates, the part 28 will be clear of this projection 6; that is, it 50 will be adjacent to a gap between two of these projections 6—which projections and gaps alternate all round the frame 5—so that the engager 26 can move up or down.

55 In this position, the catch 20 will have been disengaged from the lower plate 11, so that the plate 13 is freed; and then this upper plate 13 is raised at the front by the handle 29 of the engager 26, it being assisted by the counter-balance weights 22. When so 60 raised about the hinge, the cooked articles can be removed, and fresh batter introduced into the matrices, whereupon the upper plate 13 is again brought down by pulling down the handle 29, which brings the engager 26 into the position shown in Fig. 2;

and the frames 5 are then again revolved, when the catch 20 is immediately pressed by the inclined end of the projection 16 under or into engagement with the lower plate 11, and held there by it, and so the plate is locked. 70 And then immediately after the projecting parts 14 of the upper door 13 leave the groove 27 in the engager 26, another of the projecting parts 6 immediately comes over the inward flange 28 of the engager 26 and holds 75 it, so that it cannot of itself fly up; whereupon another of the engaging parts 14 of the next set of plates moves into the groove 27 of the engager 26 which has just been vacated by the projection 14 of the preceding set of plates. 80

The carrier frames or disks 5, with the plates, are revolved by a suitable crank 30 in the front, which operates a pinion 31, which gears with a spur wheel 35 on one of the trunnions 7 of the rotary frame; the pinion 31 and spur wheel 35 being of such a size that one revolution of the former and handle, will revolve the apparatus $\frac{1}{6}$ of a revolution in the case of the six sets of plates being employed. And the crank 30 is provided with 90 a catch 32 on the end of its pivoted handle 33, which engages with a notched inclined plate 36 on the frame, the catch 32 being normally pressed towards the plate 36 by a spring-pressed bolt 34. To disengage the 95 catch 32 from the notch in the plate 36, the handle 33 is pressed inwards, and upon releasing this pressure, at the end of a revolution, the catch reengages.

Two horns 37 are provided on the back 100 frame 3, which, when the top plate 13 is open, prevent the apparatus being revolved, as they come on each side of the hinged portion at 15 of the plate, and so should the catch 32 not be engaged with 36, the apparatus 105 cannot be revolved.

At the bottom of the machine there is a second burner or heater 10, which heats the top plates or covers 13 of the different sets, when this plate is below, so that the cooking 110 is effected on both sides.

What is claimed is:—

1. In machinery for making cup wafers, sugar wafer biscuits, and the like, of the type in which a plurality of sets of cooking plates 115 are revolved or reciprocated about an axis, and are opened and closed successively, an inner stationary plate, and an outer hinged plate having a stationary hinge connection with the inner plate, and having a detent at 120 its outer end adapted to be operated from the front of the machine; an engager device at the front end adapted to operate in connection with the outer plate 13, and an oscillating lever carrying—at its front end—125 said engager and having its axis coincident with the axis of the hinge of the plates; substantially as set forth.

2. In machinery for making cup wafers, sugar wafer biscuits, and the like, in which a 130

plurality of sets of cooking plates are revolved or reciprocated about an axis, the counterbalanced lever carrying an engager 27 having its axis separately from and coincidently with the axis of the hinge of the outer plate 13; substantially as set forth.

3. In machinery for making cup wafers, sugar wafer biscuits, and the like, of the type in which a plurality of sets of cooking plates 10 are revolved or reciprocated about an axis, a catch 20 having its hinge parallel with the plates, and carried on one of the plates (13) and adapted to move up to and away from the end of said plate, and engage and disengage with same, and projections on the stationary portion of the frame of the machine for operating it, adapted to engage with the end of such catch, and move it out of engagement and into engagement, as each pair 15 of plates come towards and leave the position in which they are emptied and charged; substantially as described.

4. Machinery for making cup wafers, sugar wafer biscuits, and the like, of the type in 25 which a plurality of sets of cooking plates or parts are revolved or reciprocated about an axis, an oscillating engaging part adapted to be engaged by projections 6 on the revolving frame having gaps between them; where- 30 by when one of the plates is disengaged from the other, when at or near the top or charging and emptying position, the outer plate is held down; substantially as described.

5. Machinery for making cup wafers, sugar 35 wafer biscuits, and the like, of the type in which a plurality of sets of cooking plates or parts are revolved or reciprocated about

an axis, having levers 25 hinged at the back of the machine, carrying in the front an engager 27, adapted to engage with a part of 40 the front end of the outer plate 13, and having an inwardly projecting flange 28 adapted to come under projections 6, disposed round the axis of the machine, and with spaces between them, when each set of plates 45 approaches the upper position; as herein set forth.

6. A machine of the class described comprising a frame, a drum revolving therein, pairs of cooking plates carried by said drum, 50 the outer plate of each pair being hinged to the inner plate, a catch on the outer plate, a projection 16 on the frame in the form of an arc of a circle with the space between its ends at the upper part of the machine, said 55 projection engaging with the end of the catch to hold it in contact with the inner plate, a projection 19 on the frame in the space between the ends of the projection 16, said projection 19 having an inclined part 17 with 60 which the end of the catch engages to free itself from the inner plate, means for lifting the outer plate off the inner plate when the catch is released and projections on the drum engaging with said means for preventing 65 said means from operating at certain intervals.

In testimony whereof I have signed my name to this specification in the presence of two subscribing witnesses.

THOMAS OWEN BATES.
